UNITED STATES PATENT OFFICE

HERM. J. HALL, OF NEW YORK, N. Y., ASSIGNEE TO UNIVERSAL OIL PRODUCTS COMPANY, OF CHICAGO, ILLINOIS, A CORPORATION OF SOUTH DAKOTA

PROCESS AND APPARATUS FOR TREATING HYDROCARBONS

Continuation of application Serial No. 410,917, filed September 17, 1929. This application filed February 6, 1930, Serial No. 66,676. Renewed November 16, 1939.

This application is a continuation of my co-pending application Serial No. 410,917, filed September 17, 1929.

This invention relates to improvements in a process and apparatus for treating hydrocarbons and refers more particularly to an apparatus adapted for the cracking of petroleum oils to produce therefrom light hydrocarbons such as gasoline or gasoline-like bodies.

Among the objects of the invention are to provide a construction in which a maximum evaporating surface is obtained for the liquid introduced into the vapor chamber; to provide a construction in which the carbon may be precipitated and collected in oil pans whereby it may be readily removed from the vapor chamber; to provide a construction in which the oil passing successively to a plurality of oil pans is retained in the vapor chamber a sufficient length of time to permit of the maximum cracking reaction; to provide a construction in which the oil containing chambers can be readily cleaned; to provide a construction in which the highest boiling vapors evolved in the lowest pans meet in their ascent surfaces of progressively higher temperature and should, in effect, be slightly superheated, thus facilitating the vaporization, completion of the reaction and the easy removal of the vaporized products from the system and in general to provide an improved construction of the character referred to.

In the drawings, the single figure shows a somewhat diagrammatic side elevation and vertical section of my improved apparatus.

Referring in detail to the drawings, 1 designates the furnace, provided with a burner 2 and stack 3. In the furnace is mounted the heating coil 4 connected to the feed line 5, leading to feed pump 6. The oil, while still in the liquid phase, passes by way of the insulated transfer line 7 into the upper part of the vertical vapor chamber 8. The transfer line 7 terminates in a nozzle 9, extending above the uppermost one of a series of oil pans 10. These oil pans, in the present instance, four being shown, are mounted on a vertically extending shaft or support 11,

13, to the bottom and top of the vapor chamber 8. The pans 10 are annular in form and are spaced apart and mounted on the shaft 11, as shown in the drawings. The pans 10 are each preferably provided with a rim 14 and with a series of preferably circumferentially extending overflow pipes 15, the arrangement being such that the liquid would overflow through the pipes 15 of one pan into the pan just below. The pans 10 are of progressively increasing diameters from the upper to the lower pan, so as to provide in the upper portion of the chamber ample space for vapors produced by the expansion of the heated oil admitted to this portion of the vapor chamber.

The overflow pipes are preferably so arranged that the overflow pipes in one pan will not be vertically above the overflow pipes in the pan below. The top plate of the vapor chamber is preferably removable so that the pans, when more or less carbon is formed therein, can be taken out and cleaned. The liquid residue is drawn off from the bottom of the vapor chamber through the line 16 having throttle valve 17 and the vapors pass out through vapor line 18 having valve 19 leading to water condenser 20. Water condenser 20 connects to a receiver 21, which receiver is provided with liquid level gauge 22 and pressure gauge 23. This receiver has a liquid drawoff line 24, controlled by throttle valve 25, and gas outlet line 26, controlled by throttle valve 27.

The novelty of the invention resides more particularly in the construction of the vapor chamber, and for the purpose of attaining the objects heretofore referred to. In operation, the oil is fed through the heating tubes where it may be raised to a temperature of, say, 800° F., and maintained under a pressure of, say, 100 pounds to the square inch. The oil, while in the liquid phase, passes into the vapor chamber and as it falls on the uppermost pan the lighter vapors will pass out of the system, the unvaporized oil falling into the pan next beneath, and so on to the bottom pan. The uncondensed vapors and gases pass out through the upper part of the vapor chamber and thence to the condenser. Suitable

aerial condensers or dephlegmators (not shown) may be used, if desired. If desired, the vapor chamber may be slightly heated by means of a burner 28, although this normally 5 will not be necessary. In addition, after the lighter oils have all been driven out of the system, it may be desirable to supply considerable heat to the bottom of the vapor chamber and drive off any oily content therein, or 10 anyway, in effect, run such residue as remains in the system down to coke.

What I claim is:

1. A continuous process for cracking hydrocarbon oil, consisting in passing the oil 15 in a stream through a heating zone wherein it is raised to a cracking temperature, in delivering the highly heated oil from said stream to an enlarged vapor chamber, collecting the oil in a plurality of vertically spaced 20 pools in said enlarged vapor chamber, said pools being of successively lower temperature and larger volume from the top to the bottom of said enlarged chamber, in permitting the oil to overflow successively from the 25 pool of highest temperature to the pool of lowest temperature, in continuously withdrawing unvaporized oil from the bottom of said enlarged vapor chamber without again admitting the same to said stream, in taking 30 off vapors from the top of said vapor chamber, in condensing such vapors, in collecting the resulting distillate and in maintaining a superatmospheric pressure on the oil undergoing treatment in the process.

35 2. A continuous process for cracking hydrocarbon oil, consisting in passing the oil through a coil disposed within a furnace wherein the oil is raised to a cracking temperature, in transferring the highly heated 40 oil from said coil to an enlarged vapor chamber, in initially delivering the oil into a relatively small pool in the upper portion of said enlarged vapor chamber, in permitting the oil to flow successively into pools of successively 45 increasing volume disposed below said first pool and maintained at successively lower temperatures, in preventing the return of any unvaporized oil from said vapor chamber to said coil, in taking off vapors from said 50 vapor chamber, in subjecting such vapors to condensation, in collecting the resulting distillate and in maintaining a superatmospheric, self-generated vapor pressure on the oil undergoing conversion in the process.

55 3. In an oil cracking apparatus, an enlarged, vertically disposed reaction chamber, means for introducing hydrocarbon oil at a cracking temperature under a superatmospheric pressure into said reaction chamber 60 adjacent the top thereof, a plurality of vertically spaced pans positioned in said reaction chamber, said pans being of successively larger cross sectional area from the topmost to the lowermost pan whereby pools of oil of 65 successively larger volume accumulate in said

reaction chamber from adjacent the top thereof, toward the bottom thereof, overflow means connected with each of said pans for maintaining a given liquid level therein, means for removing unvaporized oil from the bottom of said reaction chamber, means for taking off vaporous constituents from the top of said reaction chamber, and means for maintaining a superatmospheric pressure on the material in said 75 reaction chamber.

4. A hydrocarbon oil cracking process which comprises passing the oil in a restricted stream through a heating zone and heating the same therein to cracking temperature under sufficient superatmospheric pressure to retain a substantial portion thereof in the liquid phase, discharging the thus heated oil into the upper portion of an enlarged vapor separating zone maintained under cracking conditions and containing a plurality of receptacles adapted to retain solid matter, flowing the liquid oil downwardly through said zone, during such downward flow precipitating solid carbonaceous matter from the liquid oil in said receptacles and overflowing the liquid oil from each receptacle to the next succeeding one, collecting successively larger pools of liquid oil in the succeeding receptacles from top to bottom of the separating zone, removing vapors from the upper portion of said separating zone for condensation and separately removing unvaporized oil from the lower portion of the separating zone.
